VACUUM TUBE GRID CONSTRUCTION

Harner Selvige, Silver Spring, Md., assignor to
the United States of America as represented
by the Secretary of the Navy

Application January 15, 1945, Serial No. 572,940

2 Claims. (Cl. 250—27.5)

1

The present invention relates generally to electron tube construction and more specifically to an improved control electrode structure suitable for incorporation in tubes of all types, particularly grid-controlled gas-filled tubes.

Prior-art vapor-electric discharge devices are generally so constructed that when the individual tube becomes conductive the arc between anode and cathode touches the cathode at some random point determined by the potential distribution, with the result that the impedance of that portion of the cathode between the point thereof touched by the arc and one end thereof is included in the work or output circuit. The flow of anode current through this added impedance may consume a considerable portion of the output energy of the tube so that when the tube is employed in a detonator firing circuit the efficiency of firing may be impaired by reason of the diminution of energy available at the detonator igniter terminals. The primary object of the present invention is, therefore, to increase output energy by providing a new and improved control electrode structure that restricts current flow to that part of the cathode that is electrically proximate to the output circuit so that the impedance of a major portion thereof will not be imposed on the output circuit. This consideration is of particular importance in tubes having the filamentary type of cathode because of the high resistance of the filament.

Another object of the invention is to provide such a structure that is relatively simple in arrangement and highly efficient in operation.

For a better understanding of the invention, together with other and further objects thereof, reference is made to the following description taken in connection with the accompanying drawings, in which

Fig. 1 is an elevational sectional view of a gas-filled, grid-controlled, filament-type tube constructed in accordance with the present invention, suitably connected circuit components being diagrammatically illustrated;

Fig. 2 is a detail perspective fragmentary view illustrating the operation of the invention;

Fig. 3 is a detail perspective, fragmentary view of a modified form of grid construction suitable for incorporation in the tube represented in Fig. 1; and

Fig. 4 is a view similar to Fig. 1 showing the invention in somewhat modified form as applied to a tube of the indirectly heated cathode type.

With reference now specifically to Fig. 1 there

is illustrated therein a tube of the gas-filled grid-controlled type, indicated generally at 10, having a glass envelope 11 and an integral base carrying contact prongs 12, 13, 14, and 16. The prongs are individually electrically connected, respectively, to an anode 20, to one terminal of a filament 22, to the other terminal of the filament, and to a control electrode 24. The filament 22 is supplied with current from a battery 18. The input contacts 14, 16 are coupled to input terminals 26, 27 of a control circuit in a conventional manner. The output terminals 12, 14 are connected to a work circuit comprising an anode battery 28 and a firing heater 29 of an electrically operable primer (the other components of which are not shown), also in a manner well known to those skilled in the art. A suitable source 18 of filament current is coupled to the contacts 13, 14. Concentric with the longitudinally disposed filament 22 is a generally tubular metallic control electrode or grid 24. Disposed between the grid 24 and the envelope is a generally tubular metallic anode 20. The general arrangement of these parts may be conventional in character, as shown. An important feature of the invention, however, resides in the provision in the otherwise continuous grid 24 of one or more slots 30, 31 at the extreme ends of this electrode, whereby the grid becomes a beam-confining electrode for restricting anode current flow to that part of the filament electrically proximate to the output circuit, thereby effectively minimizing the impedance of the anode-filament current path, in a manner specifically to be explained in the following description of the operation of the electron tube.

In the filamentary type of tube, the filament is not at a uniform potential throughout its length with respect to the grid or anode because of the voltage drop in the filament caused by the flow of heating current therein. When a positive triggering potential is placed on the control electrode, one end of the filament is more negative with respect to the anode than the other end, depending upon the connections of the filament battery 18. The major flow of anode current would tend to occur at this more negative end because of the potential distribution, if the grid slot were to run the full length of the grid. The disposition of the grid slots only at each end of the filament, however, insures that the arc will strike one of the other end of the filament. In the embodiment illustrated electron flow will occur through the slot 31, since it is located adjacent to that part of the filament that is electrically prox-

mate to the negative terminal of the battery 18. This operation is illustrated in detail in Fig. 2. If the battery terminals were reversed, electron flow would occur through the slot 30. In that case, the contact 13 should be coupled to the 5 grounded side of the work circuit.

The Fig. 4 embodiment differs from that illustrated in Fig. 1 in that an indirectly heated cathode 23 and heater are substituted for the filament, and in the provision of only a single slot, 31', in the grid at the grounded end of the cathode. The contacts and circuit connections are modified accordingly in a conventional manner.

In the indirectly heated type of gas tube, the cathode is at substantially uniform potential along its length. If the grid slot were coextensive with the grid, the arc would touch the cathode at some random point. Since the grid slot 31', however, is placed near the end of the cathode to which the external cathode lead is coupled at the contact 15, anode current flows between the portion of the cathode near that end and the anode, so that a minimum of resistance is imposed on the output circuit of the tube. This portion of the cathode is electrically proximate to the output circuit. The nature of the anode-cathode current path illustrated in Fig. 2 in connection with the embodiment first described is of course similar in the embodiment of Fig. 4.

In Fig. 3 a modified form of grid construction is shown. In order to prevent deformation of the grid slot when the tube is subjected to rough handling, a reinforcing strap 34 bridging the lower margins of the grid adjacent the slot is provided. This strap, shown welded in place, might of course be punched as an integral part of the grid.

While there have been described what are at present considered to be preferred embodiments of this invention, it will be obvious to those skilled in the art that various changes and modifications may be made therein without departing from the

invention and it is, therefore, intended in the appended claims to cover all such changes and modifications as fall within the true spirit and scope of the invention.

I claim:

1. An electronic tube comprising an envelope, an anode disposed longitudinally within the said envelope, a longitudinally extending filament in spaced relation to the said anode, and a control electrode between the said anode and the said filament and substantially coextensive with the said filament, the said control electrode having at least one slot at each end thereof defining restricted paths of anode current between the said filament and the said anode.

2. A gas-filled discharge device, comprising an anode, a filament extending longitudinally within the said anode and in spaced relation thereto, and a control electrode between the filament and the anode, said control electrode having an opening at each end and being of approximately the same longitudinal extent as the said filament, the said control electrode thus shielding the filament from the anode except adjacent the ends of the said filament, and thereby forcing the electrical discharge within the gas to occur at or near an end of said filament.
